UNITED STATES PATENT OFFICE.

CHARLES J. PILLING, OF LANSDOWNE, PENNSYLVANIA, ASSIGNOR TO GEORGE P. PILLING AND CHARLES J. PILLING, OF PHILADELPHIA, PENNSYLVANIA, COPARTNERS TRADING AS GEORGE P. PILLING & SON.

DESIGN FOR A BLANK FOR SPECULA.

SPECIFICATION forming part of Design No. 35,714, dated February 11, 1902.

Application filed January 16, 1902. Serial No. 90,095. Term of patent 7 years.

To all whom it may concern:

Be it known that I, CHARLES J. PILLING, a citizen of the United States, residing at Lansdowne, State of Pennsylvania, have invented and produced a certain new and original Design for a Blank for Specula, of which the following is a full, clear, and exact description, reference being had to the accompanying drawings, forming a part of this specification.

My invention consists of the design in novel outline, planular shape, or configuration shown in said drawings of a sheet-metal blank from which a single-bladed vaginal speculum may be "struck up" by dies, as is usual with sheet-metal blanks. In its essentials it comprises a blade portion A, rounded 20 at its extreme end a, widening slightly in a longitudinal direction toward the junction d d with the handle portion B. The latter at its extreme end b is slightly curved and has substantially straight parallel sides c c, passing into a large curve to a union with the junction portion d d. The latter consists of two opposite long curves, which give a swell or widened body portion to the blank. 25

I claim as new—

The design for a blank for a single-bladed 30 speculum, substantially as shown and described.

In testimony whereof I have hereunto affixed my signature this 15th day of January, A. D. 1902.

CHARLES J. PILLING.
